UNITED STATES PATENT OFFICE.

LAWRENCE J. KLINE, OF CHICAGO, ILLINOIS, ASSIGNOR TO MERCURY MANUFACTURING COMPANY, OF CHICAGO, ILLINOIS, A CORPORATION OF ILLINOIS.

TRACTOR.

1,391,779.

Specification of Letters Patent. Patented Sept. 27, 1921.

Application filed September 27, 1920. Serial No. 412,989.

To all whom it may concern:

Be it known that I, LAWRENCE J. KLINE, a citizen of the United States, and a resident of Chicago, in the county of Cook and State 5 of Illinois, have invented certain new and useful Improvements in Tractors, of which the following is a specification, reference being had to the accompanying drawings.

My invention relates to tractors and has 10 to do particularly with the front supporting wheels and the arrangement and construction by which they are turned for steering the tractor. In the use of structures heretofore in which a single wheel has been provided 15 located centrally at the forward end of the tractor, it has been difficult to obtain the desired spring mounting without at the same time very materially weakening the lateral support of the wheel, and it is the 20 principal object of my invention to provide a new and improved form and arrangement of parts by which the tractor frame may be supported with the desired amount of resiliency and by which the tendency of the sup- 25 porting wheel structure to cant laterally is reduced to a minimum or is entirely eliminated. The preferred means by which I have accomplished my object is illustrated in the accompanying drawings and is here- 30 inafter specifically described. That which I believe to be new and desire to cover by Letters Patent is set forth in the claims.

In the drawings,—

Figure 1 is a transverse vertical section 35 through the forward end portion of my improved structure, being taken substantially on line 1—1 of Fig. 2; and

Fig. 2 is a longitudinal vertical section 40 through the parts shown in Fig. 1, being taken substantially on line 2—2 of Fig. 1.

Referring to the several figures of the drawings, in which corresponding parts are indicated by the same reference characters,—4 indicates the main frame of a tractor comprising a cross-bar 5 a short distance in rear of the forward end of the frame. A longitudinally extending plate 6 is secured 45 at its forward end to the front end of the frame 4, and at its rear end to the cross-bar 5, the plate 6 being provided with a vertically disposed sleeve 7 which is braced in position thereon by vertically disposed webs 8 and 9.

10 indicates a yoke provided with an up-

wardly extending shank 11 which extends 55 into the sleeve 7 of the plate 6. An anti-friction bearing 12 of any approved type is interposed between the yoke 10 and the sleeve 7, a felt washer 13 being provided for preventing the escape of oil therefrom. A 60 bushing 14 of bronze or of other suitable material is provided on the inner face of the sleeve 7. The upper end of the shank 11 is reduced in size and a cap 15 is secured thereon by means of screw-threads serving to 65 hold the shank against withdrawal from the sleeve 7.

The yoke 10, rotatably connected with the main frame as above described, has connected with its end portions two semi-elliptical springs 16 and 17. As is best shown in Fig. 2, each of the springs 16 and 17 comprises a plurality of leaves connected together by means of a bolt 18, the uppermost leaf being pivotally connected by means of 75 a bolt 19 with the forward end of the yoke. At the rear end of the yoke the uppermost two leaves of the spring are held in sliding engagement with the yoke by means of a pin 20.

An axle 21 is connected at a point between its ends with an intermediate portion of the springs 16 and 17 by means of clips 22, three of which are employed, one being located between the springs and the other two 85 being positioned on opposite sides of the pair of springs. Plates 23 and 24 are used in connection with the clips 22 for holding the springs and axle securely in position. As is clearly shown in Fig. 1, the axle 21 is of 90 reduced diameter at its operative end portions so as to provide shoulders adjacent to the clips 22. Supporting wheels 25 and 26 of any suitable type are secured upon the end portions of the axle 21, anti-friction 95 bearings of any suitable type being interposed between the hubs of the wheels and the axle. It has been found, from practical experience, that when the axle of the steering wheels is arranged in direct alinement 100 with the vertical turning axis, the wheels are easily turned or deflected from their forward course when traveling over rough or uneven roads. To overcome this defect of construction, the axle 21, instead of being 105 arranged in alinement with the vertical axis of the shank 11 and the steering rod 27, is rearwardly offset therefrom, as shown in

Fig. 2. By thus offsetting the axle with respect to the vertical axes of the steering rod 27 the wheels are maintained in their parallel position with the longitudinal axis 5 of the tractor which tends to render the steering much easier and also to maintain the wheels in a straight line when the tractor is moving forward.

By mounting the wheels 25 and 26 upon 10 the same axle member so as to hold the wheels rigidly in parallel position with respect to each other, the wheels are assured the required lateral support and are prevented from canting laterally with respect 15 to the yoke 10, the width of the tread of the two wheels taken together being sufficient to effect this purpose. At the same time the wheels 25 and 26 are located in sufficiently close proximity to each other to make them 20 easy to control for guiding the tractor.

Means is provided for turning the wheels with respect to the frame 4 for steering the machine. This means comprises a steering bar 27 which extends downwardly through 25 a suitable opening through the shank 11 and through the yoke 10, being keyed in said opening, as is shown in Fig. 2, so as to cause the shank to rotate therewith for turning the yoke laterally with respect to the frame.

30 For holding the bar 27 against withdrawal, I have provided a collar 28 held in position by means of a tapered pin 29, as is shown in Fig. 2, a set screw 30 carried by the cap 15 being adapted to engage a notch in the upper 35 edge of the collar 28 for preventing upward movement of the collar and the steering bar 27 and for preventing rotary movement of the cap 15 with respect to the shank 11. As will be readily understood, the cap 15 can 40 be rotated for purposes of adjustment when the set screw 30 has been turned out of contact with the collar 28. The steering bar 27 is provided upon its end portion with a handle 31 of any suitable type.

45 As will be readily understood, by the manipulation of the steering bar 27, the wheels 25 and 26 can be swung laterally with respect to the frame 4 for steering the tractor, the wheels being at so short a distance apart 50 as to afford little more resistance against a turning movement than would a single front supporting and steering wheel. By the use of the semi-elliptical springs 16 and 17, the

desired resiliency is obtained, while at the same time the wheel structure is adapted to 55 resist any tendency to cant laterally, as is above described.

What I claim as my invention and desire to cover by Letters Patent is,—

1. In a tractor, the combination of a frame, 60 a yoke journaled in said frame and rotatable about a vertical axis, a semi-elliptical spring below said yoke and connected with end portions of the yoke, said yoke and spring being bowed in opposite directions, supporting wheels located at opposite sides of said spring, an axle connecting said wheels, and means for securing the central portions of said axle and spring together. 65

2. In a tractor, the combination of a frame, 70 a yoke journaled in said frame and rotatable about a vertical axis, a pair of semi-elliptical springs placed side by side and spaced a short distance apart and each connected with end portions of said yoke, an axle extending transversely of said springs, means located between and below said springs for securing the springs and the axle together, other securing means abutting the outer sides of the springs, and wheels on the end 75 portions of said axle in proximity to said springs.

3. A tractor comprising a frame, a yoke rotatably connected with said frame, two semi-elliptical springs each connected at one 85 end with said yoke and having sliding engagement with the yoke at the other end, an axle, a clip between said springs and two other clips on opposite sides of said springs connecting said axle at an intermediate 90 point with an intermediate portion of said springs, and supporting wheels journaled on the end portions of said axle on opposite sides of said springs.

4. A tractor comprising a frame, a vertically-disposed sleeve mounted on said frame centrally thereof at its forward end, a yoke having a shank journaled in said sleeve, an antifriction bearing between said yoke and said sleeve, a cap secured to said shank 100 above said sleeve, a semi-elliptical spring carried by said yoke, and a pair of supporting wheels located a short distance apart on opposite sides of said spring, and means for connecting said wheels with said springs. 105

LAWRENCE J. KLINE.
